UNITED STATES PATENT OFFICE.

HARRY BRADSHAW, OF KANSAS CITY, MISSOURI.

PAPER FEEDING.

Application filed January 28, 1921. Serial No. 440,600.

My invention relates to improvements in paper feeding.

It relates particularly to a novel method of treating paper sheets arranged in a pile 5 preliminary to detaching the sheets from the pile.

It is well known that sheets of paper in a pile often stick together, due to the static condition of the sheets or to the outside air 10 pressure against the sheets, which renders it difficult to feed the sheets from the pile without having some of the sheets stick together.

The object of my invention is to so treat 15 the outer sheet of the pile so that a partial separation of the sheet from the pile will be effected preliminary to the operation of detaching the sheet from the pile.

My improved method effects this partial 20 separation of the sheets from the pile by heating the outer side of the outer sheet, thereby expanding the air which is between the outer sheet and the sheet next adjacent thereto, which operation permits 25 the sheet to be readily detached from the pile.

My invention provides further the application of suction to the outer side of the outer sheet for the purpose of taking hold 30 of the sheet after it has been heated.

The novel features of my invention are hereinafter fully described and claimed.

In the accompanying drawing, which 35 illustrates apparatus for carrying my invention into effect,

Fig. 1 is a view partly in elevation and partly in vertical section of an apparatus embodying one form of my invention.

Fig. 2 is a diagrammatic view showing 40 the relative positions of the three cams.

Fig. 3 is an enlarged vertical section of the nozzle shown in Fig. 1.

Fig. 4 is a vertical sectional view of another apparatus for carrying into effect another form of my invention.

Similar reference characters designate similar parts in the different views.

Referring first to Figs. 1, 2 and 3, 1 designates a pile of paper from which the 50 sheets are to be fed.

Reciprocatively mounted in a suitable support 2 is a vertically slideable member 3 having a tubular lower end to which is

55 having mounted in its lower side a per-

forate plate 5, preferably concavo-convex, the under side being concave.

Pivoted to the upper end of member 3 is a rod 6, connected to an eccentric strap 7 which embraces in the usual manner an eccentric 8, which is rigidly secured to a horizontal shaft 9 rotatably mounted in support 2 and having secured to it a pulley 10 which may be rotated by any suitable power.

11 and 12 designate respectively two pump cylinders in which are respectively vertically reciprocative two pistons 13 and 14 respectively pivoted at their upper ends to two connecting rods 15 and 16, which are respectively attached to two eccentric straps 17 and 18 mounted respectively on two eccentrics 19 and 20 which are secured to and disposed in similar positions on the shaft 9.

The cylinder 11 is connected below the piston 13 to a flexible tube 21 which at its other end communicates with the passage 22 provided in the lower end of the member 3.

A tube 23 is connected at one end with the lower end of the cylinder 12 and at its other end it is disposed so as to project a jet of heated air against the upper or outer side of the top or outer sheet of the pile 85 of paper 1.

The air passing through the tube 23 may be heated in any suitable manner, as by a coil 24 of resistance wire which encircles the tube 23 and which is located in and forms part of a suitable electric circuit.

In the operation of this form of my invention when the piston 14 descends, heated air will be discharged against the top or outer sheet of the pile of paper, thereby 95 heating this sheet and the air between this sheet and the one next adjacent thereto.

The heating of the top sheet will effect two functions. It will tend to curl the sheet upwardly and in expanding the air between the sheets, it will effect a partial separation between the two top sheets, thus enabling the top sheet being readily detached from the sheet next below. After this partial separation has been effected by the 100 heating of the top sheet, any suitable means may be employed to detach the top sheet from the pile.

In the form shown in Fig. 1, when the piston 13 moves upwardly it will effect a 110 suction through the nozzle 4 and passage

22. As illustrated in Fig. 2 the cams 19 and 20 are set a little in advance of the cam 8, so that when the nozzle 4 is against or closely adjacent to the top sheet of the pile 1, suction is being effected in the nozzle 4 which will cause the top sheet to adhere to the nozzle, so that the latter will lift the top sheet on the continued upward movement of the member 3, so that the top sheet may be readily seized by any suitable device and drawn from the pile of paper.

It will be noted that when the member 3 carrying the nozzle 4 is descending, the piston 14 will be projecting heated air against the upper side of the top sheet, thereby heating the sheet so as to effect the partial separation from the sheet next below it, so that the top sheet will be in condition for engagement with the nozzle 4 when the latter is in operative position.

Preferably the top sheet is heated at one of its corner portions, but this is not essential in carrying my invention into effect.

In the form of my invention shown in Fig. 4, the top sheet of the pile 1 is heated by means of an ordinary electric heater of any ordinary type having a downwardly facing deflector 25 and a central heating coil 26. This electric heater is disposed above the pile in a position such that it will quickly heat the top sheet of the pile. After being heated in this manner, the top sheet may be detached by any suitable mechanism, such as a horizontal roller 27 having perforations disposed radially therein and designated by 28 and arranged to consecutively communicate with a radial opening 29 provided in the under side of a horizontal tubular shaft 30 on which the perforated rollers 27 is rotatably mounted.

When the roller 27 is rotated in the direction indicated by the arrow in Fig. 4 and bears against the top sheet of the pile, and a partial vacuum is created in the tubular shaft 30, suction will be created which will cause the top sheet to adhere to the roller 27, which will cause the previously heated sheet to be slid from the pile. Any suitable means may be employed to drive the roller 27 and to create a partial vacuum in the tubular shaft 30.

With the use of my invention the top sheet can be reliably separated from the one next below and liability of two sheets sticking together and being withdrawn at one time from the pile will be eliminated.

I do not limit my invention to the structures shown and described, as many modifications within the scope of the appended claims may be made without departing from the spirit of my invention.

What I claim is:

1. In feeding sheets of paper from a pile,

the method consisting in projecting heated fluid against the outer side of the outer sheet preliminary to the removal of the sheet from the pile, substantially as set forth.

2. In feeding sheets of paper from a pile, the method consisting in projecting heated air against the outer side of the outer sheet preliminary to the removal of the sheet from the pile, substantially as set forth.

3. In feeding sheets of paper from a pile, the method consisting in projecting heated fluid against the outer side of a corner portion of the outer sheet preliminary to the removal of the sheet from the pile, substantially as set forth.

4. In feeding sheets of paper from a pile, the method consisting in projecting heated air against the outer side of a corner portion of the outer sheet preliminary to the removal of the sheet from the pile, substantially as set forth.

5. In feeding sheets of paper from a pile, the method consisting in projecting heated air against the outer side of the outer sheet and then applying suction to the outer side of the sheet in the operation of detaching the sheet from the pile, substantially as set forth.

6. In feeding sheets of paper from a pile, the method consisting in projecting heated air against the outer side of the outer sheet and then lifting the sheet by suction in the operation of detaching the sheet from the pile, substantially as set forth.

7. In feeding sheets of paper from a pile, the method consisting in projecting heated air against the outer side of a corner portion of the outer sheet and then lifting by suction said portion in the operation of detaching the sheet from the pile, substantially as set forth.

8. In feeding sheets of paper from a pile, the method consisting in projecting heated air against the outer side of the outer sheet, and then withdrawing the sheet from the pile, substantially as set forth.

9. In feeding sheets of paper from a pile, the method consisting in projecting heated air against the outer side of the outer sheet, then applying suction to the outer side of the sheet, and then detaching the sheet from the pile, substantially as set forth.

10. In feeding sheets of paper from a pile, the method consisting in projecting heated air against the outer side of the outer sheet, then lifting by suction the sheet, and then detaching the sheet from the pile, substantially as set forth.

In testimony whereof I have signed my name to this specification.

HARRY BRADSHAW.
